UNITED STATES PATENT OFFICE.

VERNON EDLER, OF LOS ANGELES, CALIFORNIA.

AUTOMOBILE LIFT.

Application filed September 29, 1926. Serial No. 138,483.

My invention relates to improvements in auto lifts in which there are two vertical cylinders arranged below a floor and each having its lower end connected with an oil tank adopted to be connected with a compressed air supply, pistons slidably arranged in the cylinders and provided with tubular stems having on their upper ends head caps carrying cross bars having mounted on their outer ends two beams each having two slots in which the ends of the cross bars are arranged, and two rollers mounted on each end of each cross bar and adopted to carry the beams when the latter move endwise on the cross bars.

The object of my invention is to provide a mechanism to be used in garages for lifting automobiles so repairmen can work on them to much better advantage.

20 Description of figures on drawings

I attain the results mentioned above by means of the mechanism illustrated in the accompanying drawings, in which—

25 Fig. 1 is a side elevation of my auto lift shown partly in section;

Fig. 2 a view of the same showing the auto supporting frame in an elevated position;

Fig. 3 a top view of my auto lift;

30 Fig. 4 a detail view showing one of the cross bars, its four rollers, the ends of the beams and a fragment of the upper end of a piston stem and its head cap; and

Fig. 5 a side view of the stem cap.

35 Detail description of the drawings.

In the drawings like reference numerals refer to the same parts throughout the several views.

40 Referring to the drawings in detail—

The reference numeral 1 represents the cement floor which supports the mechanism. Near each end of the mechanism is a cylinder 2 having at its upper end a flange 3 flush with the top of the floor. The lower end of each cylinder has a cap 4 and is connected by a pipe 5 with an oil tank 6 having at its upper end an oil pipe 7 and a pipe 8 for connection with a compressed air supply.

50 Seated on the floor over each cylinder flange 3 is a flat ring 9 secured to the cement floor by bolts 10. Interiorly fitting the upper end of each cylinder and the opening in the flat ring 9 is a tubular ring 11 having a flange 12 seated on the ring 9 and secured to the flange 3 by bolts 14.

Slidably arranged in each cylinder is a piston 15 carrying two packing rings 16 and having a tubular stem 17 having on its upper end a head cap 18 having therethrough a horizontal opening 19 in which there is secured a cross bar 20.

On each side of the top of the mechanism is a T iron 21, herein referred to as a beam, because something other than T iron could be used, and having near its ends slots 22, 23 in which are arranged the ends of the cross bars 20. On each end of each cross bar are two rollers 24, one on either side of the beam. Said rollers are adapted to engage the under side of the beam flanges and carry the weight of the beams. Each pair of rollers is held in place by two pins 30.

At one end of each beam its flanges are shown cut away and a reinforcing plate 26 secured to each side of the beam. In the upper edges of each pair of the said plates and in the beam is a notch 27 having in its bottom a vertical slot 28. The beams are preferably connected by two braces 29 to provide a rigid frame.

In using the mechanism the operation is as follows:

The auto is driven lengthwise over the frame from left to right so the rear axle is directly over the notches 27 at the ends of the beams. Compressed air is then caused to enter the oil tanks thereby forcing the oil into the lower ends of the cylinders and raising the pistons and the frame. With the rear axle seated in the notches 27, the truss rods in the slots 28 and the front axle resting on the top of the beams the auto is elevated to such height and position as will afford greatest convenience for the workman. When thus elevated the frame may be horizontal, or on an incline as indicated by the dotted lines Fig. 2. When one end of the frame is elevated more than the other the ends of the cross bar at the higher end of the frame move away from the inner end of the slots in proportion to the incline, the rollers carrying the load thus preventing friction between the cross bars and the upper edge of the slots. Being able to thus elevate an auto quickly is a great convenience when either repairing, cleaning or painting cars, and saves time and expense. It is a great convenience to have a car thus elevated even when only changing tires because the operator can stand up and have the wheel directly in front of him while he works.

105

110

Both ends of each beam could be equipped with the reinforced plates 26 so an auto could if desired be driven over it from either direction.

5 One oil tank could be used in place of two in which case each cylinder would be connected with the same oil tank and means provided for controlling the flow of oil through each pipe together with means for 10 regulating the passage of air into and out of the oil tank.

The ends of one cross bar could be arranged in slots in the beams as shown and the ends of the other cross bar rotatable 15 arranged in round openings, except that the slots in that case would need to be longer, than when four are used, to allow sufficient movement of the bar ends when the frame is tilted.

20 Having thus described my invention what I claim as new and desire to secure by Letters Patent, is—

1. In an automobile lift, two vertical cylinders arranged below a floor, pistons slidably arranged in said cylinders and each provided with a stem having on its upper end a head cap having therethrough a horizontal opening, a horizontal cross bar secured in each of the horizontal openings in 25 said head caps, two parallel beams each having a top flange on either side and each having two longitudinal slots in its vertical wall, the ends of the said cross bars being arranged in said slots, a roller rotatably 30 mounted on each end of each cross bar on either side of the beam, said rollers engaging the under side of the said flanges and carrying the beams, the beams when raised being adapted to engage the under side of 35 the axles of an automobile and elevate the latter, two oil tanks arranged below the floor, means for connecting the oil tanks with the cylinders and a compressed air supply, and means for controlling the pressure 40 in the oil tanks whereby the beams may be raised or lowered at will.

2. In an automobile lift, a floor having therethrough two vertical openings each having an annular groove at its top, cylinders 50 suspended in said floor openings and provided at their upper ends with exterior annular flanges seated in said annular grooves, flat rings seated on said cylinder flanges and having their outer edges overlapping 55 and secured to the floor, tubular rings interiorly fitting the openings in the said flat rings and the upper ends of the cylinders and having at their upper ends annular flanges seated on the said flat rings and secured to 60 the cylinder flanges by bolts passed through openings in the tubular ring flanges and the flat rings and the cylinder flanges, pistons slidably arranged in said cylinders and provided with stems interiorly and slidably

fitting the said tubular rings, head caps 65 secured to the upper ends of said piston stems and adapted when idle to rest on and be supported by said tubular rings, a horizontal cross bar carried by each of said head caps, two parallel automobile lifting beams 70 carried by said cross bars and adapted when an automobile is driven over them to engage its axles and lift the car, an oil tank connected with the cylinders and with a compressed air supply, and means for controlling the pressure in the oil tank and cylinders whereby the beams may be raised and lowered as desired.

3. In an apparatus for lifting automobiles, a floor provided with an opening having an annular groove at its top, a cylinder provided at its upper end with an annular flange fitting said annular groove, a flat ring seated on said cylinder flange and having its outer edge overlapping and secured to the floor, a tubular ring interiorly fitting the opening in the flat ring and the upper end of the cylinder and having at its upper end an annular flange seated on said flat rings and secured to the said cylinder flange by bolts passed through openings in the tubular ring flange and the flat ring and the cylinder flange, a piston arranged in the cylinder and provided with a stem interiorly fitting the tubular ring, a cross bar secured to the upper end of the piston stem, two beams carried by the cross bar and adapted to lift an automobile, an oil tank connected with the cylinder and with a compressed air supply, and means for controlling the pressure in the oil tank and cylinder whereby the beams may be raised and lowered.

4. In an apparatus for lifting automobiles, means for automobiles to travel on, two vertical cylinders arranged below said means and provided with a piston having a stem, a cross bar secured to the upper end of each piston stem, two beams mounted on the ends of the cross bars and each having on either side at its top a flange and each having in its vertical wall near one end a longitudinal slot, the ends of one cross bar being arranged in said slots, a roller rotatably mounted on each end of the latter cross bar on either side of each beam and adapted to engage the under side of the flanges on either side of the beam and carry the latter, two oil tanks having their lower ends connected with the lower ends of the cylinders, means for connecting the upper ends of the oil tanks with a compressed air supply, and means for controlling the pressure in the tanks and cylinders whereby an automobile above the apparatus may be raised and lowered by the said beams.

In testimony whereof I affix my signature.

VERNON EDLER.
